(57) **ABSTRACT**

A developing apparatus includes a developer conveyance member including a rotatably supported flexible sheet having a first distance between its rotation axis and an edge of the flexible sheet in a state where the flexible sheet is unbent. A lid of a developing container includes a corner portion that extends a storage space outward of an imaginary circle with a radius of the first distance centered on the rotational axis, and a contact portion which protrudes from an inner surface of the corner portion to an inner side of the imaginary circle and with which the flexible sheet contacts while the conveyance member is being rotated. The contact portion has a distal edge shaped such that a distance between the distal edge and the rotation axis increases toward a downstream side in a rotation direction of the conveyance member as viewed in the direction along the rotation axis.

DEVELOPING APPARATUS HAVING A FLEXIBLE DEVELOPER CONVEYOR

BACKGROUND OF THE INVENTION

Field of the Invention

The present invention relates to a developing apparatus to be used in an electrophotographic image forming apparatus.

Description of the Related Art

In an image forming apparatus that uses an electrophotographic image forming method, developer is typically stored in a developer container and successively supplied to a developing apparatus. The developer is typically conveyed from the developer container to the developing apparatus by using a rotational agitation member, which includes a flexible agitation sheet.

The agitation member is supported inside the developer container. As the agitation member rotates, the flexible agitation sheet may transition repeatedly between a state, in which the agitation sheet is in contact with the frame of the developer container and is thus bent, and a state, in which the agitation sheet is separate from the frame and released from bending. The difference between bent state and release state can be great especially with a downsized developer container, thus increasing the fatigue of the agitation sheet. In this respect, Japanese Patent Application Publication No. 2015-129812 describes a configuration including ribs that come into contact with the agitation sheet to prevent the release noise generated when the sheet is released.

SUMMARY OF THE INVENTION

The present invention further improves conventional techniques, and it is an object of the present invention to provide a developing apparatus that is downsized and has an increased capacity but still suppresses the fatigue of agitation sheets.

To achieve the above objective, a developing apparatus according to the present invention includes:

a developing container having a first opening and a second opening;

a lid fixed to the developing container so as to close the first opening, the lid defining, together with the developing container, a storage space for developer;

a developing roller provided so as to face the second opening; and

a conveyance member configured to convey a toner toward the developing roller through the second opening in the developing container, the conveyance member including a flexible sheet and a support member that supports the sheet and is rotatable about a rotation axis together with the sheet, the sheet having a first distance between the rotation axis and an edge of the sheet in a direction orthogonal to the rotation axis in a state in which the sheet is unbent, wherein the lid includes:

a corner portion that, as viewed in a direction along the rotation axis, extends the storage space outward of an imaginary circle with a radius of the first distance centered on the rotational axis; and

a contact portion that protrudes from the corner portion to an inner side of the imaginary circle and is configured to come into contact with the rotating sheet.

2

As described above, the present invention provides a developing apparatus that is downsized and has an increased capacity but still suppresses the fatigue of agitation sheets.

Further features of the present invention will become apparent from the following description of exemplary embodiments with reference to the attached drawings.

BRIEF DESCRIPTION OF THE DRAWINGS

10 FIG. 1 is a cross-sectional view of the principal section of a developing unit;

FIG. 2 is a cross-sectional view of an apparatus main body and a cartridge of an image forming apparatus;

FIG. 3 is a cross-sectional view of the cartridge;

15 FIG. 4 is a perspective view illustrating the configuration of the cartridge;

FIG. 5 is a perspective view illustrating the configuration of the cartridge;

FIGS. 6A and 6B are cross-sectional views of guide portions of the image forming apparatus for illustrating the attachment of the cartridge;

FIGS. 7A and 7B are cross-sectional views of the image forming apparatus for illustrating the positioning of the cartridge;

20 FIGS. 8A to 8D are perspective views illustrating a configuration in which the cartridge receives driving force from the apparatus main body;

FIG. 9 is a perspective view illustrating the configuration of the developing unit;

30 FIG. 10 is a cross-sectional view of the principal section of the developing unit;

FIG. 11 is a cross-sectional view of the principal section of the developing unit;

FIG. 12 is a cross-sectional view of the principal section of a developing unit; and

35 FIG. 13 is a cross-sectional view of the principal section of a developing unit.

DESCRIPTION OF THE EMBODIMENTS

40 Hereinafter, a description will be given, with reference to the drawings, of embodiments (examples) of the present invention. However, the sizes, materials, shapes, their relative arrangements, or the like of constituents described in the embodiments may be appropriately changed according to the configurations, various conditions, or the like of apparatuses to which the invention is applied. Therefore, the sizes, materials, shapes, their relative arrangements, or the like of the constituents described in the embodiments do not intend to limit the scope of the invention to the following embodiments.

First Embodiment

55 Referring to the drawings, an embodiment of the present invention is now described.

A direction along the rotation axis of the electrophotographic photosensitive drum is referred to as a longitudinal direction. In the longitudinal direction, the side in which the 60 electrophotographic photosensitive drum receives driving force from the image forming apparatus main body is referred to as a drive side, and the opposite side is referred to as a non-drive side.

Referring to FIGS. 2 and 3, the overall configuration and 65 an image formation process are now described. FIG. 2 is a cross-sectional view of an apparatus main body (electrophotographic image forming apparatus main body, image form-

ing apparatus main body) A and a process cartridge (hereinafter referred to as a cartridge B) of the electrophotographic image forming apparatus according to the embodiment of the present invention. FIG. 3 is a cross-sectional view of the cartridge B. The apparatus main body A is a portion of the electrophotographic image forming apparatus excluding the cartridge B.

Overall Configuration of Electrophotographic Image Forming Apparatus

The electrophotographic image forming apparatus (image forming apparatus) shown in FIG. 2 is a laser beam printer using an electrophotographic technique in which the cartridge B is attached to the apparatus main body A in a detachable manner. When the cartridge B is attached to the apparatus main body A, an exposure apparatus 3 (laser scanner unit) is arranged that forms latent images on an electrophotographic photosensitive drum 62, which serves as an image bearing member of the cartridge B. A sheet tray 4, which is arranged under the cartridge B, stores recording medium such as recording paper or plastic sheet (hereinafter referred to as sheet material PA) on which images are formed. The electrophotographic photosensitive drum 62 is a photosensitive member (electrophotographic photosensitive member) used to form electrophotographic images.

The apparatus main body A further includes a pickup roller 5a, a pair of feeding rollers 5b, a transfer guide 6, a transfer roller 7, a conveyance guide 8, a fixing apparatus 9, a pair of discharge rollers 10, and a discharge tray 11, which are arranged along the conveying direction D of the sheet material PA. The fixing apparatus 9 includes a heating roller 9a and a pressing roller 9b.

Image Formation Process

The outline of the image formation process is now described. In response to a print start signal, the electrophotographic photosensitive drum (hereinafter referred to as photosensitive drum 62 or simply as drum 62) is driven to rotate in the arrow R direction at a predetermined circumferential speed (process speed). A charging roller (charging member) 66, to which a bias voltage is applied, is in contact with the outer circumferential surface of the drum 62 and uniformly charges the outer circumferential surface of the drum 62 (see FIG. 3).

The exposure apparatus 3 outputs a laser beam L according to image information. The laser beam L passes through the laser opening 71h provided in a cleaning frame 71 of the cartridge B, and scans the outer circumferential surface of the drum 62 to perform exposure. An electrostatic latent image corresponding to the image information is thus formed on the outer circumferential surface of the drum 62.

As shown in FIG. 3, a developing unit 20, which serves as the developing apparatus, includes a toner chamber 29 storing toner T. A conveyance member (agitation member) 43 rotates to agitate and convey the toner T to a toner supply chamber 28. The magnetic force of a magnet roller 34 (stationary magnet) holds the toner T on the surface of a developing roller 32. The developing roller 32 is a developer carrying member that carries developer (toner T) on its surface to develop the latent image formed on the drum 62. A developing blade 42 friction-charges the toner T and controls the layer thickness of the toner T on the circumferential surface of the developing roller 32, which serves as the developer carrying member.

The toner T is supplied to the drum 62 according to the electrostatic latent image to develop the latent image. As a result, the latent image is formed as a visible toner image. The drum 62 is an image bearing member that bears a latent image or an image to be formed with toner (toner image,

developer image) on its surface. As shown in FIG. 2, the sheet material PA stored in a lower portion of the apparatus main body A is sent out from the sheet tray 4 by the pickup roller 5a and the pair of feeding rollers 5b in time with the output of a laser beam L. The sheet material PA is conveyed along the transfer guide 6 to the transfer position between the drum 62 and the transfer roller 7. At this transfer position, the toner image is sequentially transferred from the drum 62 to the sheet material PA.

10 The sheet material PA to which the toner image is transferred is conveyed away from the drum 62 and to the fixing apparatus 9 along the conveyance guide 8. The sheet material PA then passes through the nip portion of the heating roller 9a and the pressing roller 9b of the fixing apparatus 9. The fixing process of pressing and heating at the nip portion fixes the toner image on the sheet material PA. The sheet material PA that has undergone the toner image fixing process is conveyed to the pair of discharge rollers 10 and discharged to the discharge tray 11.

15 As shown in FIG. 3, the residual toner on the outer circumferential surface of the drum 62 after transferring is removed by a cleaning member 77 and used for an image formation process again. The toner removed from the drum 62 is stored in a waste toner chamber 71b of a cleaning unit 20. The cleaning unit 60 is a photosensitive drum unit including the photosensitive drum 62.

20 In the foregoing description, the charging roller 66, the developing roller 32, the transfer roller 7, and the cleaning member 77 function as a process unit for acting on the drum 62.

Overall Cartridge Configuration

Referring to FIGS. 3, 4, and 5, the overall configuration of the cartridge B is now described. FIG. 3 is a cross-sectional view of the cartridge B, and FIGS. 4 and 5 are perspective views illustrating the configuration of the cartridge B. In this embodiment, the description of the screws for connecting parts is omitted.

35 The cartridge B includes the cleaning unit (photosensitive member holding unit, drum holding unit, image bearing member holding unit, first unit) 60 and the developing unit (developer carrying member holding unit, second unit) 20.

40 As shown in FIG. 3, the cleaning unit 60 includes the drum 62, the charging roller 66, the cleaning member 77, and a cleaning frame 71, which supports these components. 45 On the drive side, the drum 62 includes a drive-side drum flange 63, which is rotationally supported by a hole portion 73a of a drum bearing 73 (see FIG. 4). In a broad sense, the drum bearing 73 and the cleaning frame 71 can be collectively referred to as a cleaning frame.

50 As shown in FIG. 5, on the non-drive side, a drum shaft 78 is press-fitted into a hole portion 71c formed in the cleaning frame 71 so that a hole portion (not shown) of the non-drive-side drum flange is rotationally supported. The drum flanges are portions that are rotationally borne and 55 supported by the respective bearing portions.

55 As shown in FIG. 3, the charging roller 66 and the cleaning member 77 of the cleaning unit 60 are in contact with the outer circumferential surface of the drum 62.

60 The cleaning member 77 has a rubber blade 77a, which is a blade-shaped elastic member made of rubber as an elastic material, and a support member 77b supporting the rubber blade. The rubber blade 77a substantially extends in the direction opposite to the rotation direction of the drum 62 and is in contact with the drum 62. That is, the rubber blade 65 77a is in contact with the drum 62 with its distal edge portion pointing toward the upstream side in the rotation direction R of the drum 62. The waste toner removed from the surface

of the drum 62 by the cleaning member 77 is stored in the waste toner chamber 71b defined by the cleaning frame 71 and the cleaning member 77.

As shown in FIG. 3, a scooping sheet 65 for preventing waste toner from leaking from the cleaning frame 71 is provided at an edge of the cleaning frame 71 in contact with the drum 62.

The charging roller 66 is rotationally attached to the cleaning unit 60 through charging roller bearings 67 located at opposite ends in the longitudinal direction of the cleaning frame 71. The longitudinal direction of the cleaning frame 71 (the longitudinal direction of the cartridge B) is substantially parallel to the direction in which the rotation axis of the drum 62 extends (axial direction). Hereinafter, the longitudinal direction and the axial direction therefore refer to the axial direction of the drum 62 unless otherwise specified.

Urging members 68 press the charging roller bearings 67 toward the drum 62, thereby pressing the charging roller 66 against the drum 62. The charging roller 66 is driven and rotated by the rotation of the drum 62.

As shown in FIG. 3, the developing unit 20 includes the developing roller 32, a developing container 600 supporting the developing roller 32, and a developing blade 42. The developing roller 32 is rotationally attached to the developing container 600 through bearing members 26 (FIG. 4) and 27 (FIG. 5) provided at opposite ends.

The developing roller 32 contains the magnet roller 34. The developing unit 20 includes the developing blade 42 for controlling the toner layer on the developing roller 32. As shown in FIGS. 4 and 5, spacing members 38 are attached to opposite ends of the developing roller 32. The spacing members 38 are brought into contact with the drum 62, so that the developing roller 32 is held with a small gap created between the developing roller 32 and the drum 62. As shown in FIG. 3, a spout prevention sheet 33 for preventing the toner from leaking from the developing unit 20 is provided at an edge of the developing container 600 and in contact with the developing roller 32. A conveyance member 43 is provided in the toner chamber 29 defined by the developing container 600 and a lid 601. The conveyance member 43 agitates the toner stored in the toner chamber 29 and conveys the toner to the toner supply chamber 28.

As shown in FIGS. 4 and 5, the cartridge B is formed by combining the cleaning unit 60 and the developing unit 20. To join the developing unit 20 to the cleaning unit 60, the center of a first developing-side support boss 26a of the bearing member 26 is aligned with a first suspension hole 71i on the drive side of the cleaning frame 71, and the center of a second developing-side support boss 27a of the bearing member 27 is aligned with a second suspension hole 71j on the non-drive side. Specifically, the developing unit 20 is moved in the direction of arrow G so that the first and second developing-side support bosses 26a and 27a are fitted into the first and second suspension holes 71i and 71j. The developing unit 20 is thus movably connected to the cleaning unit 60. Specifically, the developing unit 20 is rotationally (pivotally) connected to the cleaning unit 60. That is, the developing roller 32 is coupled to the drum 62 so as to be movable toward and away from the drum 62. Then, the drum bearing 73 is coupled to the cleaning unit 60 to form the cartridge B.

In this embodiment, a non-drive-side urging member 46L (FIG. 5) and a drive-side urging member 46R (FIG. 4) are compression springs. The urging force of the springs allows the drive-side urging member 46R and the non-drive-side urging member 46L to urge the developing unit 20 to the cleaning unit 60, ensuring that the developing roller 32 is

pressed in the direction of the drum 62. The present embodiment also includes the spacing members 38 at opposite ends of the developing roller 32. That is, the drum 62 is in contact with the developing roller 32 through the spacing members 38 with a predetermined contact pressure, so that the developing roller 32 is held with a predetermined gap created between the developing roller 32 and the drum 62. The relative positions of these components are thus determined.

Cartridge Attachment

Referring to FIGS. 6A, 6B, 7A, and 7B, the attachment of the cartridge B is now described in detail. FIG. 6A is a cross-sectional view of the drive-side guide portion of the image forming apparatus A for illustrating the attachment of the cartridge B. FIG. 6B is a cross-sectional view of the non-drive-side guide portion of the image forming apparatus A for illustrating the attachment of the cartridge B. FIG. 7A is a cross-sectional view of the drive side of the image forming apparatus A for illustrating the positioning of the cartridge B. FIG. 7B is a cross-sectional view of the non-drive side of the image forming apparatus A for illustrating the positioning of the cartridge B.

The cartridge B is attached as follows. As shown in FIGS. 6A and 6B, a first drive-side plate 15 includes an upper guide rail 15g and a guide rail 15h as guides, and a non-drive-side plate 16 includes a guide rail 16d and a guide rail 16e. The drum bearing 73 provided on the drive side of the cartridge B has a rotation stop target portion 73c. The cartridge B is attached in a direction (arrow C) substantially perpendicular to the axis of the drum 62 (FIG. 3).

The cleaning frame 71 includes, on the non-drive side in the longitudinal direction, a positioning target portion 71d as a first positioning portion and a rotation stop target portion 71f as a second positioning portion. When the cartridge B is attached through a cartridge insertion slot 17 of the apparatus main body A, the guide rail 15h of the apparatus main body A guides the rotation stop target portion 73c of the cartridge B on the drive side of the cartridge B. On the non-drive side of the cartridge B, the guide rails 16d and 16e of the apparatus main body A guide the positioning target portion 71d and the rotation stop target portion 71f of the cartridge B. The cartridge B is thus attached to the apparatus main body A.

The closing of an opening/closing door 13 is now described. As shown in FIGS. 6A, 6B, 7A, and 7B, the first drive-side plate 15 has an upper positioning portion 15a, a lower positioning portion 15b, and a rotation stop portion 15c as positioning portions, and the non-drive-side plate 16 has a positioning portion 16a and a rotation stop portion 16c. The drum bearing 73 includes a positioning target portion (first positioning target portion, first protrusion, first bulging portion) 73d and a positioning target portion (second positioning target portion, second protrusion, second bulging portion) 73f.

Cartridge pressing members 1 and 2 are rotationally attached to opposite axial ends of the opening/closing door 13. Cartridge pressing springs 19 and 21 are attached to the longitudinal ends of the front plate of the image forming apparatus A. The drum bearing 73 has a pressing target portion 73e as an urging force receiving portion, and the cleaning frame 71 has a pressing target portion 710 on the non-drive side (see FIG. 3). When the opening/closing door 13 is closed, the cartridge pressing members 1 and 2 urged by the cartridge pressing springs 19 and 21 of the apparatus main body A press the pressing target portions 73e and 710 of the cartridge B (see FIGS. 7A and 7B).

As a result, on the drive side, the upper positioning target portion 73d, the lower positioning target portion 73f, and the

rotation stop target portion **73c** of the cartridge B are fixed to the upper positioning portion **15a**, the lower positioning portion **15b**, and the rotation stop portion **15c**, respectively, of the apparatus main body A. The cartridge B and the drum **62** are thus positioned on the drive side. Likewise, on the non-drive side, the positioning target portion **71d** and the rotation stop target portion **71f** of the cartridge B are fixed to the positioning portion **16a** and the rotation stop portion **16c**, respectively, of the apparatus main body A. The cartridge B and the drum **62** are thus positioned on the non-drive side.

The above description of an example of the configuration for positioning the cartridge B relative to the apparatus main body A is not intended to limit the means for positioning. A configuration may be used that directly acts on the positioning target portion **73d** and the rotation stop target portion **73f** on the drive side of the cartridge B, and the positioning target portion **71d** and the rotation stop target portion **71f** on the non-drive side to fix the positioning portions.

Referring to FIGS. 8A, 8B, 8C, and 8D, the configuration in which the cartridge B receives driving force from the apparatus main body A is now described. FIG. 8A is a diagram showing the configuration of a drive portion of the apparatus main body A. FIG. 8B is a diagram showing the configuration of a drive portion of the cartridge B. FIG. 8C is a diagram showing a state before the drive portions of the apparatus main body A and the cartridge B are engaged. FIG. 8D is a diagram showing a state in which the power of the apparatus main body A is turned on and the drive portions of the apparatus main body A and the cartridge B are engaged.

As shown in FIG. 8A, the apparatus main body A includes a drive transmission member **81**, which receives driving force from a driving source (not shown) of the apparatus main body A and transmits the driving force to the cartridge B. As shown in FIG. 8B, the cartridge B includes a driven portion **63b** in the drive-side drum flange **63** to engage with the drive transmission member **81** and receive the driving force. When the opening/closing door **13** is closed and the power of the apparatus main body A is turned on, the drive transmission member **81** moves in the direction of arrow E in FIG. 8C. Then, as shown in FIG. 8D, a drive transmission portion **81b** of the drive transmission member **81** engages with the driven portion **63b** of the drive-side drum flange **63**, and the drum **62** is rotated through the drive-side drum flange **63**. The outer circumference of the drive transmission member **81** has a gear shape **81g**. Additionally, a developing roller gear **90** is coupled to an end of the developing roller **32** of the cartridge B. When the driven portion **63b** of the drive-side drum flange **63** is engaged as shown in FIG. 8D, the gear shape **81g** on the drive transmission member **81** and the developing roller gear **90** are arranged so as to mesh with each other. That is, when the drive transmission member **81** rotates the drum **62** through the drive-side drum flange, the developing roller gear **90** also rotates simultaneously through the developing roller gear **90**.

Configuration of Developing Unit 20

Referring to FIG. 9, the configuration of the developing unit **20** is described in further detail. FIG. 9 is a perspective view illustrating the configuration of the developing unit **20**.

As shown in FIG. 9, the developing container **600** is integrally joined, at a first opening **600a**, with the lid **601**, which is a first base member, by a joining member such as welding. The conveyance member **43** includes a shaft member **43a** (support member) and a conveyance sheet member **43b** (sheet) as a sheet member. The conveyance sheet member **43b**, which is a flexible member, is fixed to the shaft member **43a** by a fixing member such as snap fit, heat

caulking, or double-sided tape. That is, the shaft member **43a** supports the conveyance sheet member **43b**. The shaft member **43a** includes a drive opening **43a1** for driving input from the outside and a cylindrical supported portion (not shown). When the developing container **600** and the lid **601** are joined, the conveyance member **43** is placed within the developing container **600** and supported so as to be rotatable about a rotation axis **A1** (rotation axis) and relative to the developing container **600**. The lid **601** is located opposite to the developing roller **32** with respect to the conveyance member **43**. As such, the capacity of the developing unit **20** can be changed simply by replacing the lid **601** with a smaller second base member **602** (see FIG. 13). This allows the assembly steps to be easily changed when the capacity of the developing container **600** varies among production lots. When the conveyance member **43** rotates about the rotation axis **A1** of the conveyance member **43** and if the conveyance sheet member **43b** maintains its natural state (natural length), the circle that is traced by the sheet distal edge portion **43b1** of the conveyance member **43** is referred to as a rotation path **43r** of the conveyance member **43** (see FIG. 1). The “natural length” used herein refers to the distance (first distance) between the rotation axis **A1** of the shaft member **43a** and an edge of the conveyance sheet member **43b** in a direction perpendicular to the rotation axis **A1** in a state in which the conveyance sheet member **43b** is unbent. That is, the circle (rotation path **43r**) that is traced by the sheet distal edge portion **43b1** is an imaginary circle having a center on the rotation axis **A1** and a radius of the first distance.

The drive-side end of the shaft member **43a** has the drive opening **43a1**, which faces the developing container **600**. The developing container **600** has a hole **600n** (see FIG. 9), which faces the drive opening **43a1**. A conveyance gear **93** is inserted into the hole **600n** from the outer side in the longitudinal direction of the developing container **600** and engages with the drive opening **43a1** inside the developing container **600**. The conveyance gear **93** is connected to the developing roller gear **90** by a first idler gear **91** and a second idler gear **92** so as to be driven. The drive transmission member **81** drives the developing roller gear **90** to rotate the conveyance gear **93**. The rotation of the conveyance gear **93** rotates the conveyance member **43**. A conveyance sealing member **94** is compressed between the conveyance gear **93** and the developing container **600**. The conveyance sealing member **94** is made of a material with sufficient cushioning characteristics and adhesiveness, such as urethane foam. The conveyance sealing member **94** is in close contact with the conveyance gear **93** and the developing container **600**, thereby preventing the toner in the developing container **600** from leaking to the outside through the hole **600n**.

Description of Developing Frame

Referring to FIGS. 1, 10, and 11, the configuration of the developing unit **20** is described in further detail. FIG. 1 is a cross-sectional view of the principal section of the developing unit **20** including the developing container **600**. As shown in FIG. 1, the developing unit **20** stores toner **T** in the storage space defined by the developing container **600** and the lid **601**. FIG. 10 is a cross-sectional view illustrating the support configuration of the conveyance member **43**. FIG. 11 is a partial cross-sectional view of the drive-side end of the developing unit **20** as viewed from the non-drive side in the longitudinal direction.

As shown in FIG. 1, a developer sealing wall **600b** divides the developing container **600** into a developing portion **600c** and a developer storage portion **600d**. The developer storage portion **600d** includes the above-mentioned conveyance

member 43, and is formed by the developer sealing wall 600b, an upper wall 600e, a first opening 600a, and a lower wall 600g. The developer sealing wall 600b has a second opening 600h, which provides communication between the developer storage portion 600d and the developing portion 600c. The conveyance member 43 conveys toner T to the developing portion 600c through the second opening 600h. The section of the developer sealing wall 600b located below the second opening 600h is referred to as a lower sealing wall 600b1, and the section above the second opening 600h is referred to as an upper sealing wall 600b2.

The developing portion 600c includes the developing roller 32, the developing blade 42, a developing blade back seal 600j, and a developing roller lower sheet 602. The developing roller 32 faces the second opening 600h. That is, the conveyance member 43 conveys the toner T toward the developing roller 32 through the second opening 600h. This configuration allows the toner T conveyed to the developing portion 600c to be carried on the developing roller 32 with a constant layer thickness as the developing roller 32 rotates. Additionally, the configuration limits leakage of the toner T from the developing portion 600c. An inclined portion 600k is formed between the second opening 600h and the developing roller 32. The inclined portion 600k is continuous with the lower sealing wall 600b1. The developing blade back seal 600j and the inclined portion 600k are parts of the developing container 600, while the developing blade 42 and the developing roller lower sheet 602 are directly fixed to the developing container 600 (not shown).

The lid 601 is fixed to the developing container 600 at the first opening 600a of the developing container 600. The lid 601 includes an upper wall 601a, a first inclined surface 601b, a second inclined surface 601c, and a concave arcuate wall 601d (arcuate surface). The first and second inclined surfaces 601b and 601c each form, with a horizontal plane, an angle that allows the toner T to fall under its own weight (the angle of repose) or greater (an angle greater than or equal to the angle of repose). The arcuate wall 601d is continuous with the lower wall 600g, which is the base surface of the developing container 600. The lid 601 further includes ribs 601f extending across the upper wall 601a and the first and second inclined surfaces 601b and 601c. The ribs 601f serve as contact portions configured to come into contact with the conveyance sheet member 43b. Each rib 601f extends across the first and second inclined surfaces 601b and 601c and along a plane perpendicular to the rotation axis. The ribs 601f are provided at intervals in the longitudinal direction (ribs 601/1 to 601/3, see FIG. 9).

The relationship between the above-mentioned components and the rotation path 43r of the conveyance member 43 is now described. As shown in FIG. 1, a part of the inclined portion 600k in the developing portion 600c is at the inner side of the rotation path 43r. The inclined portion 600k faces toward the rotation center A1 of the conveyance member 43. The inclined portion 600k is an inclined surface extending from the lower edge of the second opening 600h such that the distance from the rotation center A1 (rotation axis) of the conveyance member 43 gradually increases from the upstream side to the downstream side in the rotation direction S of the conveyance member 43. The lid 601 includes a region (corner portion 601g) that extends the toner storage space outward of the rotation path 43r. Of the space defined by the upper wall 601a, the first inclined surface 601b, and the second inclined surface 601c, the corner portion 601g defines a space that is outside the rotation path 43r. The ribs 601f located in this corner portion 601g each have the shape of a rib protruding to the inner side

of the rotation path 43r. Each rib 601f is formed so that the distance from the rotation center A1 increases from the upstream side to the downstream side in the rotation direction S.

According to the configuration described above, the inclined portion 600k faces toward the rotation center A1, and the distance between the inclined portion 600k and the rotation center A1 increases in the rotation direction S. Consequently, the conveyance sheet member 43b is gradually released from bending while in contact with the inclined portion 600k (see also FIG. 10). This allows the toner T on the inclined portion 600k to be conveyed in the direction of the developing roller 32, achieving the efficient use of the toner T in the developing portion 600c. Also, the bending of the conveyance sheet member 43b is released gradually, reducing the noise (release noise) generated when the conveyance sheet member 43b is released from a bent state.

Furthermore, the lid 601 includes the corner portion 601g, which is outside the rotation path 43r, allowing the toner T to be stored outward of the rotation path 43r. The developing unit 20 can thus have a larger capacity.

Moreover, the ribs 601f, which protrude into the inner side of the rotation path 43r, are located in the corner portion 601g. As such, the conveyance member 43 rotates with its distal edge portion 43b1 constantly in contact with the developing container 600 or the lid 601 except when the distal edge portion 43b1 reaches the developing portion 600c (see also FIG. 11). This reduces the occasions in which the conveyance sheet member 43b is released from a bent state, thereby reducing the release noise. The configuration also reduces the fatigue fracture, which would otherwise occur due to repeated bending and releasing of the conveyance sheet member 43b.

Each rib 601f is shaped such that the distance from the rotation center A1 increases in the rotation direction S. As such, when the conveyance sheet member 43b moves from the upper wall 600e and along the ribs 601f, the bending of the conveyance sheet member 43b is gradually released without fluctuations. This reduces the occasions in which the conveyance sheet member 43b is released, further limiting the generation of release noise and fatigue fracture. The ribs 601f are located in a region having an angle greater than or equal to the angle of repose in the inner surface of the corner portion 601g forming the storage space. The arcuate wall 601d, which has an angle less than the angle of repose, does not have a rib. This allows the conveyance sheet member 43b to come into contact with the arcuate wall 601d and thus convey the toner T on the arcuate wall 601d.

Other Embodiments

As shown in FIG. 12, the conveyance member 43 may include a second sheet member 43c, which may be fixed to the developer sealing wall 600b by heat welding or other means. The second sheet member 43c may be fixed to the developer sealing wall 600b with a fixing force that allows the second sheet member 43c to be peeled off from the developer sealing wall 600b when the conveyance member 43 rotates at the beginning of use of the cartridge B, thereby opening the second opening 600h. As such, when the cartridge B is unused, the developer sealing wall 600b and the second sheet member 43c separate the developer storage portion 600d from the developing portion 600c to prevent leakage of the toner T during its distribution and storage.

FIG. 13 shows another embodiment in which the lid 601 is replaced with a second base member 603 including ribs 603f that extend along planes perpendicular to the rotation

11

axis of the conveyance member 43 and are configured to come in contact with the conveyance sheet member 43b as contact portions. The second base member is shaped so that the inner surface defining the toner storage space is located inside the rotation path of the conveyance member 43. As such, the amount of toner T stored in the developing unit 20 can be changed. Each rib 603f is shaped such that the distance from the rotation center A1 gradually increases from the upstream side to the downstream side in the rotation direction S, thereby reducing the occasions in which the conveyance sheet member 43b is released.

This embodiment reduces the fatigue of the conveyance sheet member 43b in the developing apparatus whose storage capacity for developer can be changed simply by replacing the base member. This embodiment also reduces the release noise of the conveyance sheet member 43b. Furthermore, the toner T in the developing portion 600c is used efficiently.

While the present invention has been described with reference to exemplary embodiments, it is to be understood that the invention is not limited to the disclosed exemplary embodiments. The scope of the following claims is to be accorded the broadest interpretation so as to encompass all such modifications and equivalent structures and functions.

This application claims the benefit of Japanese Patent Application No. 2020-102663, filed on Jun. 12, 2020, which is hereby incorporated by reference herein in its entirety.

What is claimed is:

1. A developing apparatus comprising:
a developing container having a first opening and a second opening;
a lid fixed to the developing container so as to close the first opening, the lid defining, together with the developing container, a storage space for developer;
a developing roller provided so as to face the second opening; and
a conveyance member configured to convey the developer toward the developing roller through the second opening in the developing container, the conveyance member including a flexible sheet and a support member that supports the flexible sheet and that is rotatable about a rotation axis together with the sheet, the flexible sheet having a first distance between the rotation axis and an edge of the flexible sheet in a direction orthogonal to the rotation axis in a state where the flexible sheet is unbent,
wherein the lid includes:
a corner portion that, as viewed in a direction along the rotation axis, extends the storage space outward of an imaginary circle with a radius of the first distance centered on the rotational axis; and
a contact portion which protrudes from an inner surface of the corner portion to an inner side of the imaginary circle and with which the flexible sheet is configured to contact while the conveyance member is being rotated, the contact portion having a distal edge that

12

is shaped such that a distance between the distal edge and the rotation axis increases toward a downstream side in a rotation direction of the conveyance member as viewed in the direction along the rotation axis.

2. The developing apparatus according to claim 1, wherein, as viewed in the direction along the rotation axis, an inner surface the corner portion of the lid has a concave arcuate surface located below a region that includes the contact portion in a state where the developing apparatus is in an apparatus body of an image forming apparatus, and

wherein the arcuate surface is continuous with a bottom surface of an inner surface of the developing container defining the storage space in the state where the developing apparatus is in an apparatus body of an image forming apparatus.

3. The developing apparatus according to claim 1, wherein, as viewed in the direction along the rotation axis, an inner surface of the developing container defining the storage space is located at the inner side of the imaginary circle.

4. The developing apparatus according to claim 1, wherein the contact portion is one of a plurality of ribs, the plurality of ribs each extending in a direction perpendicular to the rotation axis, and
wherein the plurality of ribs are spaced apart in the direction along the rotation axis.

5. The developing apparatus according to claim 1, wherein the developing roller is located opposite to the conveyance member across the second opening.

6. The developing apparatus according to claim 1, wherein a part of a sealing member that seals the second opening is fixed to the conveyance member in a state where the developing apparatus is brand-new, and the conveyance member is configured to rotate to peel off the sealing member from the second opening to open the second opening.

7. The developing apparatus according to claim 1, wherein in a state where the developing apparatus is in an apparatus body of an image forming apparatus, an inner surface of the developing container has a bottom surface below the conveyance member, and wherein the inner surface of the corner portion of the lid has a region which slopes downward toward the bottom surface of the developing container as viewed in the direction along the rotation axis.

8. The developing apparatus according to claim 1, wherein the conveyance member is arranged between the first opening and the second opening of the developing container.

9. The developing apparatus according to claim 1, wherein the developing apparatus is a cartridge detachably attached to the apparatus body of the image forming apparatus.
